UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

CHANGEABLE ROTARY FOLDER.

Application filed September 13, 1924, Serial No. 737,552. Renewed February 9, 1928.

This invention is a novel improvement in folding mechanisms for web printing presses especially designed for use in connection with newspaper printing presses and the object of the invention is to make a folder which can be adapted to fold newspapers of different sizes by the substitution of interchangeable parts of the desired size at a very slight expense.

10 Ordinarily large newspaper presses are built to order, and generally are made to print papers of one of three given sizes in length, say approximately 21 $\frac{1}{2}$ ", 22 $\frac{3}{4}$ " and 23 $\frac{3}{8}$ ".

15 With such a press a folder is always required of proper size to fold the papers produced by such machine. Such folder is built with cutting and folding rolls adapted to handle the particular length of sheet for

20 which the press is built.

The cylinder, frames, gearing, etc., of the press, and the folder, are not usually manufactured until the order determining the size of sheets to be printed, is received by the manufacturer, as it would throw an immense financial burden on manufacturers to carry different sizes of such large machines in stock. It not infrequently happens that a publisher after purchasing one or more presses and folders adapted to print and fold a given size of sheet finds conditions changed which make it advantageous to alter the size of sheets. Heretofore in such cases to make such a change has required the expenditure of a large amount of money and time to exchange the presses and folders for new ones of the required size.

Heretofore when the size of sheet is changed it has always been necessary to also exchange the old folder for a new folder of the required size. In my companion application (Case #7073) for patent on rotary printing press, I have shown and described a novel newspaper press so constructed that if the newspaper owner desires to change the size of the sheets of the newspapers to be printed, he can do so by removing from such press the original plate and impression cylinders and substituting therefor plate and impression cylinders adapted to print the size of sheets desired, and by changing a few gears, whereupon the press is capacitated to print the desired length of sheet, and the owner is not compelled to purchase an en-

tirely new press in order to make the desired change in size of sheets. When such changes are made, however, he would ordinarily have to buy a new folder to handle the new size of sheets, and the primary object of the present invention, as above stated, is to enable the press owner in such case to use the original folder attached to his original press by substituting for the original cutting and folding rollers in such folder other cutting and folding rollers of proper size to handle the new size of sheet, the other parts of the folder remaining the same, with the minor exceptions and adjustments hereinafter noted; so that when the owner changes his printing press to print a different size of sheet;—or if he buys a new printing press, to print a different size of sheet, he can use the old folder by changing it at little expense to suit the new size of sheet.

To enable others skilled in the art to readily understand and utilize the invention I will explain it more in detail with reference to the accompanying drawings which illustrate one practical embodiment thereof; and refer to the appended claims for summaries of the essentials of the invention, the novel features of construction, and novel combinations of parts, for all of which protection is desired.

In said drawings:

Figure 1 is a side elevation of a rotary folder having folding cylinders say 14 $\frac{1}{2}$ " in diameter and its parts adjusted to fold one given size of sheets.

Figure 2 is a side elevation of such folder arranged to fold another size of sheet, and having a folding cylinder, say 15" in diameter.

Figure 3 is an end elevation showing the principal mechanisms of the folder.

Figure 4 is an enlarged detail view of the parts which require shifting or replacing when altering the folder to suit the size of sheets to be folded.

The folder illustrated in the drawings, shows a double folder having duplicate sets of folding mechanisms which can simultaneously operate on separate webs in the usual manner. As each of the two folders is constructed and operated alike a description of one will explain both, similar reference characters indicating similar parts.

Each web of paper w is led from the press (not shown) in the usual manner to and over a former indicated at F in the drawings, and between the guide rolls 1 down between 5 pinch rolls 2, then between a cutting cylinder 3 and folding cylinder 4. The cut sheet is discharged from the folding cylinder 4 by a tucker (of usual form) carried by cylinder 4 between folding rollers 5, and the 10 folded sheets drop into a reel 6 which transfers them to the delivery belts 7. The parts thus far described are or may be constructed as usual in single or double folders.

As shown, all the folding mechanism is 15 mounted in a common frame 20. The cylinder 3 and folding cylinder 4 with their component parts, such as cutting knives, tucker blades, retaining pins, and gears 3^a, 4^a, whose pitch lines correspond with the respective 20 cylinders, are bodily removable from the frame and are interchangeable with like cutting and folding cylinders of a different size. When it is desired to change the folder so as to operate upon a different size of sheet 25 the cylinders 3 and 4 are removed and other cylinders substituted therefor adapted to fold the new size of sheet. The bearing 4^b for the folding cylinder 4 may remain always in the same place, and in fact may be 30 formed integral with or as a part of the sides 20 of the frame. The bearings 3^b of the cutting cylinder 3 are made adjustable toward or from the bearings 4^b, and when the cylinders are changed the bearing 3^b 35 is adjusted to suit the diameters of the substituted cutting and folding cylinders. The bearings 3^b may be made adjustable in any suitable manner, as by slotting the bolt holes, by drilling new bolt holes in the bearings 40 or side frames 20; or by substituting another bearing provided with holes drilled to match the holes already drilled in side frames 20.

Figure 4 diagrammatically indicates two sizes of cylinders 3, 3' and two sizes of interchangeable folding cylinders 4, 4' and the corresponding different positions of the adjustable bearings 3^b. When the folding cylinders are changed the second fold rolls 5, should be adjusted so that they can properly 45 cooperate with the folding cylinder. For this purpose the second fold rolls 5 are supported in adjustable brackets 8 (see Figures 3 and 4) which are adjustably attached to the side frames 20, so that they can be 50 vertically adjusted thereon in order to move the second fold rolls 5 bodily toward or from the folding cylinder 4. The rolls 5 in each pair revolve in opposite directions, and one of these rolls carries a gear 5^a which is 55 driven by an intermediate gear 5^b from a gear 4^c on the shaft of the related cylinder 4.

The other roll 5 in each pair is driven 60 from its companion roll. As indicated in Figure 4 the driven roll 5 carries a pinion

5^d meshing with an intermediate pinion 5^e in turn meshing with an intermediate pinion 5^f meshing with a pinion 5^g on the second roll 5. Pinions 5^e and 5^f can be mounted on the bracket 8 if desired. To avoid confusion of lines in the drawings generally only the pitch circles of the various gears have been indicated.

Each pair of second fold rolls 5 must be 65 located in close proximity to the related cylinder 4. When a cylinder 4 is replaced by another of different size, (as 4' in Figure 4) rolls 5 must be adjusted to a new position. In the construction shown as the second fold rolls and their operating mechanisms are 70 carried on the adjustable brackets 8, (one at each side of the folder or at each end of the rolls) by adjusting the brackets 8 the entire second fold roll mechanism can be 75 adjusted to a position corresponding to the size of the cylinder (4 or 4'), as indicated in Figures 1, 2 and 4. The brackets 8 can be made adjustable in the frames 20 in any desired manner, as by slotting the bolt holes as shown in Figure 4, or new holes may be 80 drilled in the frame to suit the new position of the brackets.

The entire folding machine is driven by 85 means of a shaft preferably connected with the main shaft driving the press. As shown, 90 the folder has a vertical drive shaft 12 driven by a bevel gear 12^a meshing with a bevel gear 11^a on a shaft 11 which is preferably directly connected with the main 95 driving shaft (not shown) of the press. Thus the folder is driven as a complete 100 machine in exact unison with the press.

The shaft 12 drives each group of mechanism in the folder; such groups consisting of drag roll above former (not shown) as 105 one group, the pinch rolls 2 as another, the fold cylinders 4 as the third group; the reels 6 as the fourth group, and the delivery belts 7 as the fifth group, as shown.

Pinch rolls 2, 2 are driven by means of a 110 bevel gear 2^c on one of the pinch rolls of each pair engaging a beveled gear 13^a on a counter shaft 13 which is driven by a beveled gear 13^b from a gear 12^a on shaft 12.

Each folding cylinder 4, or 4' is driven 115 by a beveled gear 4^c on its shaft, meshing with a beveled gear 14^a on a counter shaft 14 which is driven by a gear 14^b from a beveled gear 12^c on shaft 12.

Each pair of second fold rolls 5 is driven 120 from a gear on the related folding cylinder shaft as above described.

Each reel 6 is driven by means of gears 6^a on the reel shaft meshing with a bevel gear 15^a on a counter shaft 15 driven by a 125 gear 15^b meshing with a gear 12^c on shaft 12.

Each delivery belt 7 is driven by wheels 7^a below the related reels 6 which wheels are driven by spiral gears 7^b on the wheel shaft meshing with a spiral gear 16^a on a counter 130

shaft 16 which might be driven by bevel gears direct from the shaft 12 if desired, but for convenience, in the construction shown, shaft 16 is driven by a gear 16^b meshing with a spur gear 15^c on shaft 15.

This construction allows variations to be made in the group of cylinder mechanism, and if necessary the group of pinch roll mechanism; without disturbing any of the 10 other groups.

It will be seen that when a change is made in the length of a newspaper to be folded; it is only necessary to substitute the cylinders 3 and 4 by cylinders of the proper 15 size and to reposition the bearings 3^b of the cutting cylinder 3 and also reposition the second fold rolls supports or brackets 8; and with the possibility in some cases (i. e. for same sizes of sheets) reposition the pinch 20 rolls 2. All the other parts of the folder can be used, and remain practically unchanged; and thus I obviate the necessity of buying a new folder when the size of the pages printed by the press is changed.

25 I claim:

1. A rotary folder having cutting and folding cylinders interchangeable with like cutting and folding cylinders of different size in order to cut and fold different lengths 30 of sheets; means for relatively adjusting the cylinders in the folder according to their size; second fold rolls adapted to receive the sheets from the folding cylinder; and means for adjusting the second fold rolls in accordance with the size of the folding cylinder.

2. A rotary folder having cutting and folding cylinders interchangeable with like cutting and folding cylinders of different size 40 to cut and fold different lengths of sheets; means for relatively adjusting the cylinders in the folder according to their size; second fold rolls adapted to receive the sheets from the folding cylinder; means for adjusting the second fold rolls in accordance with the size of the folding cylinder; and means for

driving the second fold rolls from the folding cylinder.

3. A rotary folder having interchangeable cutting and folding cylinders adapted to cut 50 and fold different lengths of sheets; second fold rolls to receive sheets from the folding cylinder; means for adjustably supporting said rolls whereby the same may be adjusted toward or from the bearings of the folding 55 cylinder in accordance with the size of the cylinder, and gearing for driving the second fold rolls from the folding cylinder.

4. A rotary folder having pinch rolls; interchangeable cutting and folding cylinders 60 adapted to cut and fold different lengths of sheets; second fold rolls to receive sheets from the folding cylinder; means whereby the second fold rolls may be adjusted toward or from the bearings of the folding cylinder 65 in accordance with the size of the cylinder, gearing between the second fold rolls; and gearing for driving the second fold rolls from the folding cylinder.

5. A rotary folder having interchangeable 70 cutting and folding cylinders adapted to cut and fold different lengths of sheets; a set of second fold rolls to receive sheets from the folding cylinder; adjustable brackets bodily carrying said rolls whereby the same 75 may be adjusted toward or from the folding cylinder in accordance with the size of the cylinder; and gearing for driving the second fold rolls in time with the folding cylinder.

6. A rotary folder having its cutting and folding cylinders removable and interchangeable with other cutting and folding cylinders for cutting and folding different lengths of sheets; means for adjusting the said cylinders in the machine according to 80 their size; second fold rolls adapted to co-operate with the said cylinders; and means for adjusting said second fold rolls in accordance with the size of the cylinders.

In testimony that I claim the foregoing as 90 my own, I affix my signature.

HENRY F. BECHMAN.
